UNITED STATES PATENT OFFICE.

JAMES L. O'CONNOR, OF NEW YORK, N. Y.

HAME-FASTENER.

SPECIFICATION forming part of Letters Patent No. 416,852, dated December 10, 1889.

Application filed January 14, 1889. Serial No. 296,356. (No model.)

To all whom it may concern:

Be it known that I, JAMES L. O'CONNOR, a citizen of the United States, and a resident of New York, in the county of New York and State of New York, have invented a certain new and useful Improvement in Hame-Buckles, of which the following is a specification.

My invention relates to improvements in metallic buckles or clasps in conjunction with a tightening device.

The object of my invention is to provide a means whereby the divided ends of a strap or inclosing-band may be drawn nearer together and while in that position buckled firmly. I attain these objects by the mechanism illustrated in the accompanying drawings, in which—

Figure 1 is a top view of the buckle when clasped. Fig. 2 is a side view of the buckle when closed and in the act of opening. Fig. 3 is a vertical section of the buckle, taken on the line $\alpha\alpha$. Fig. 4 is a horizontal section of the buckle applied as a trunk-fastening or otherwise.

Similar numbers refer to similar parts throughout the drawings.

In Fig. 1, the part 1 represents the buckle and leverage device. The part 2 is the metallic strap. The said buckle and strap are each secured to the opposite ends of the hames by loops 33, riveted thereto by bolts 44. The metallic strap 2 is provided with slots 5 at regular intervals.

The buckle part 1 consists of a metallic strap with two flanges 66, these flanges being provided with concave grooves 77. The lever 8 is hinged to the flanges 66 at points 99 and is provided with convex edges at the points 7'7', made to fit into the concave grooves 77, when it is forced down between the flanges 66 and is clasped thereby. The said lever is also provided with the tongue 10, hinged in the slot 11, into which it fits when the buckle is clasped. The said tongue is provided with flanges 13, which prevent it dropping too deeply into the slots 5, and is also provided with teats 14 and 15. The said lever 8 is also provided with teat 16 on the under side thereof. The teats 14, 15, and 16 are arranged, when the buckle is closed, to lock through the slots 5 in the strap 2 and into the sockets

provided therefor in the part 1—that is to say, the slot or sockets 17, 18, and 19. The lever 8, near its extremity, is punctured with two holes 2020, from which two parallel slots 2121 are cut to the extremity of the lever, thus leaving free fingers on the sides of the lever. The extremities of these fingers are provided with right-angled extensions 7'7', which stand upon the surface of the lever 8 and serve as thumb-buttons, which may be grasped between the thumb and forefinger of the hand and the extremities of the fingers pressed toward one another. The exterior edges 7'7' of the fingers are made convex or beveled to a line in the center, and the interior of the sides of the buckle are cut with grooves. The exterior edges 7'7' of the fingers on the sides of the lever 8 are of such a size that when the lever 8 falls between the sides of the buckle the fingers will be pressed together and will slip into the grooves 77.

Secured to the side of the buckle is a loop 25, to which the yoke-strap may be attached. This loop may either be rigidly riveted into the buckle, or, as shown in Fig. 1, eyes may be riveted into the buckle, and into these eyes a swinging loop may be secured.

The operation of my invention I prefer to illustrate as applied to the tightening and buckling of hames; but it may be used for any purpose to which it is applicable. The parts 1 and 2 are fastened to the lower ends of the hames by the link 33, riveted to each at 44. The ends of the strap and buckle are then brought together and the strap introduced at 23, and the strap caused to pass through the buckle as far as the pressure of the hand will unite the divided hames. At this point the lever 8 is thrown back and the tongue 10 permitted to reach its full length and the hook at the end thereof to drop into one of the holes in the strap. Pressure is then applied to the knob 22 and the parts 1 and 2 caused thereby to be drawn together to a certain point, where the lever 8 is pressed into its seat between the flanges 66. The clasps 2121, yielding to pressure exerted, permit the parts 7 and 7'7' and 7' to clasp together, and by these it is firmly held, the teats 14, 15, and 16 dropping into their respective slots, thus lending strength and se-

curity to the buckle. The operation of opening the buckle is that of pressing together the split lever 21 21 and at the same time lifting the lever 8 by the knob 22 out of its seat.

5 Having thus described my invention, what I claim, and desire to secure by Letters Patent, is—

1. In a fastening device, the combination of a frame, a lever pivoted to the frame at one of its extremities, a tongue pivotally attached to the lever and provided on its free end with means for engaging and holding the strap, a strap arranged to pass through the frame, and a holding device in the rear of the tongue adapted to engage and hold the strap, substantially as described.

2. In a fastening device, the combination of a frame, a lever pivoted to the frame at one of its extremities, a tongue pivotally attached to the lever, a strap arranged to pass through the frame and in position to be engaged by the tongue, and a catch located upon the frame and lever in position to engage and hold the lever and frame together when the device is closed, substantially as described.

Signed at New York, in the county of New York and State of New York, this 17th day of December, A. D. 1888.

JAMES L. O'CONNOR.
